UNITED STATES PATENT OFFICE

ROBERT A. CURRIE, OF SYRACUSE, NEW YORK, ASSIGNOR TO R. E. DIETZ COMPANY, OF NEW YORK, N. Y.

LANTERN

Application filed October 23, 1928. Serial No. 314,397.

This invention relates to lanterns, and has for an object to provide an improved lantern in which complete combustion of various grades of fuel may be obtained without smoking.

Another object of the invention is to provide an improved lantern of the type having a globe confined to its seat by a movable chimney or flue element, in which the flue element may be adjusted to vary the effective length of the flue thereof and permit use of the lantern with different grades of fuel oil; in which the adjustment of the effective length of the flue may be made independently of the movement of the flue element as a unit to release or engage the globe; in which the sections of the flue element may be secured releasably in different adjusted positions; in which the flue element may be operated as a unit to release or grip the globe while in all adjusted positions; in which disengagement of the flue element or any section thereof from the frame of the lantern will be prevented when said flue element is released in the absence of a globe from its seat.

Another object of the invention is to provide an improved lantern which will be exceptionally compact for shipping purposes, and in which the flue or chimney element may be varied in length to provide the necessary and suitable draft when the lantern is used for burning various different grades of fuel oil, and in which unintentional changes in the flue length may be prevented.

Another object of the invention is to provide an improved lantern construction which will accomplish each and all of the above objects, and which will be relatively simple, durable, compact and inexpensive.

Various other objects and advantages will appear from the following description of two embodiments of the invention, and the novel features will be particularly pointed out hereinafter in the appended claims.

In the accompanying drawing:—

Fig. 1 is a side elevation of a lantern constructed in accordance with this invention, with the flue element shown by full lines in one adjusted position and by dash lines in another adjusted position;

Fig. 2 is a partial elevation similar to Fig. 1, but illustrating the chimney element by full lines in the position occupied by it when in the dash line position of Fig. 1;

Fig. 3 is a central sectional elevation of the same, when the flue element is in the position shown by full lines in Fig. 1;

Fig. 4 is a sectional plan of the same, with the section taken approximately along the line 4—4 of Fig. 3;

Fig. 5 is a sectional elevation similar to Fig. 3, but illustrating the flue element in the adjusted position shown in Fig. 2;

Fig. 6 is an elevation partly in section of a lantern also constructed in accordance with the invention, but illustrating a slightly different embodiment of the invention;

Fig. 7 is a sectional plan of the same, with the section taken approximately along the line 7—7 of Fig. 6.

In the embodiment of the invention illustrated in Figs. 1 to 5, the lantern has any suitable or usual oil fount and base 1, and tubular frame members 2 extend upwardly from the base and support a bell or chimney guard 3. The base 1 mounts a burner box 4 upon which is seated a globe plate or seat 5, which plate may be elevated or lowered by the usual globe plate operating lever 6.

A transparent globe 7 is demountably supported upon the globe plate or seat 5 between the tubular frame members 2, and the globe terminates at its open upper end below the bell or chimney guard 3. The guard 3, which is tubular, may be open at both ends, and at its upper end has an inturned flange 8. A cylindrical guide or collar 9 is mounted in the interior of the chimney guard 3 below the inturned flange 8, extends in a direction endwise of the guard, and terminates at its lower end in an inturned flange 10.

A flue element 11 passes through the guard 3 and is formed of two telescopic sections 11a and 11b, and the smaller or inner section 11a extending upwardly through and sliding in the aperture formed by the flange 8, and the larger or outer section 11b extending through and being slidably mounted in the guide 9.

The lower section 11b, adjacent its upper

end, is reduced in diameter so as to provide a shoulder 12, and the extreme upper or reduced end 13 fits and slides upon the outer periphery of the inner or upper section 11a. The larger 5 end or portion of the lower section 11b, at a point adjacent the shoulder 12, is provided with an externally projecting peripheral bead 14, which may be spun therein, that slides along the inner cylindrical wall of the collar 10 or guide 9. The bead 14, by engaging with the inturned flange 10 of the guide 9, limits downward movement of the lower section 11b of the flue element and thus prevents disengagement of the section 11b from the guide 9. 15 A helical spring 15 surrounds the upper section 11a of the flue element, and is compressed between the flange 8 of the guard and the shoulder 12 on the lower section 11b of the flue element, so as to urge the lower section 11b yieldingly in a downward direction 20 through the guide 9.

The lower end of the section 11b of the flue element fits over a reduced upper end of the globe 7 to hold the globe upright and form 25 a continuation of the flue of the globe for conducting away gases of combustion and providing the necessary chimney action or draft for the purposes of combustion of the flame within the globe.

20 The lower end of the upper or inner section 11a is provided with an outwardly extending flange 16 which closely approaches the inner periphery of the larger portion of the lower section 11b, so that flue gases rising from the globe 7 will be conducted upwardly through 25 the upper or inner section 11a of the flue element. The upper end of the section 11a of the flue element may also be provided with a peripherally projecting bead 17, that may 30 be spun therein if desired, which may engage with the outer end face of the flange 8 to limit downward movement of the upper section of the flue element. The flue element at its upper end may have the usual vent apertures 18, 35 and a dome or cap 19 carrying the finger piece 20 by which the flue element may be shifted upwardly to release the globe 7.

One of the sections of the flue element 11, such as the upper or inner section 11a, is provided in the overlapping portion of the telescoping sections, with one or more slots 21, each of which extends endwise of the flue element for some distance and terminates in or 50 opens into lateral branches 22. A pin 23 is 55 carried by the reduced end 13 of the other section 11b and projects through the slot 21.

This pin 23, when in the vertical or endwise stretch of the slot 21, permits free endwise relative movements of the two flue sections 11a and 11b, to an extent permitted by the engagement of the pin with the ends of the endwise stretch and in alignment with the end lateral branches 22 of the slot.

60 Thus the flue element may have its effective length, that is, the effective length of the

passage or flue thereof, lengthened or shortened by relative endwise movements of the sections. When the effective length of the element is increased, the length of the flue 70 producing a draft in the globe 7 will be increased, and the lantern will burn without smoking, the relatively heavy or crude fuel oils which may be encountered. When the effective length of the flue element is shortened, such as by moving the upper section 75 11a downwardly into the lower section 11b, as shown in Figs. 1 and 3, the length of the flue passage connected to the upper end of the globe 7 will be shortened, and the lantern 80 will function properly without smoking while burning the higher or better grades of fuel oil.

By slightly rotating one of the sections, such as the upper section 11a, relatively to the lower section 11b, the pin 23 may enter one of the lateral branches 22, and while in that lateral branch, it will releasably lock the two flue sections together, so that they may be shifted together vertically as a unit to engage with or release the upper end of the globe 7.

The flue element 11 will be yieldingly urged downwardly by the spring 15, and this spring will yield when the flue element is drawn upwardly by the finger piece 20 to release the globe 7, and also when the globe 7 is elevated by levers 6 for the purpose of lighting the burner. If the globe should be removed, and the flue element then released, the spring 15 will urge the flue element downwardly until stopped by the engagement of the bead 14 with the flange 10, the bead 14 and flange 10 serving as cooperating stops or abutments to limit this downward movement of the flue or chimney element. The flue elements 11a and 11b may be provided with suitable ventilating apertures as usual in the art, but such apertures per se form no part of the present invention, and perform their usual function.

The embodiment of the invention illustrated in Figs. 6 and 7 is substantially identical to this extent with the embodiment illustrated in Figs. 1 to 5 and similar parts are designated by similar reference characters. 115 In Figs. 1 to 5 two sets of slots 21 and 22 may be provided upon diametrically opposite sides of the flue element, and the pins 23 may be the inturned or angular ends of a semi-circular spring arm 24 which rests upon the shoulder 12 of the lower flue section. The free ends of arm 24 may be sprung apart, inserted in suitable apertures in the reduced end 13 of the flue element, and allowed to enter the slots 21 and 22. The pins 23 are therefore the angular terminals of the semi-circular spring arm or strip 24, and the two flue sections may be quickly released by merely springing apart the free ends of the 120 125 130

strip or arms 24, to carry the pins 23 out of the slots 21 and 22.

In Figs. 6 and 7, the pin 23 is formed by an inturned or angular end of the spring 15.

5 The pin 23 may be shifted out of interlocking engagement with the sections of the flue element by merely springing outward the lower end or terminal of the spring 15, and obviously this pin 23 operates in only one slot 21. 10 The use or operation, however, of the lantern is the same in both embodiments of the invention.

The vertical or endwise slots 21 may obviously have as many lateral branches 22 as may be desired into which the pins 23 may be shifted, so as to lock the flue element sections in different telescopic or adjusted positions by the limited relative rotary movement of the telescopic sections. Thus the effective length 20 of the flue element which serves as a chimney may be made selectively adjustable in length or height, and may be adjusted by the user until it is suitable for the quality of oil that is being burned.

25 The flue element may also be shortened, that is, the extent to which it projects above the chimney guard 3 may be decreased, so that it may be packed in a relatively small box or carton, which greatly reduces the freight charges and the cost of packing, and this is an important advantage in shipments to distant points. The flue element never becomes disengaged from the chimney guard, even when released in the absence of the globe 7. 35 The adjustment of the flue element or chimney may easily be learned by relatively ignorant or unskilled persons, and without any extended or special training.

It will be obvious that various changes in the details, which have been herein described and illustrated in order to explain the nature of the invention, may be made by those skilled in the art within the principle and scope of the invention as expressed in the appended claims.

Claims:—

1. A lantern comprising a globe seat, a globe on said seat, a chimney guard, a flue element engaging the upper end of said globe to confine it to its seat and formed of two telescopic sections, and a spring acting between said guard and one of said sections of said element to yieldingly press said element against said globe, the other section of said element being adjustable endwise to vary the effective length of the chimney element, said section having portions selectively interlocking with one another to enable operation of said sections together to release the globe.

60 2. A lantern comprising a globe seat, a globe on said seat, a chimney guard, a flue element engageable with the upper end of said globe to confine it to said seat and formed of telescopic sections, a spring acting between said guard and that end section of said ele-

ment which engages with said globe for urging said section yieldingly into engagement with said globe, said section and said guard having cooperating stop portions limiting movement of said section toward said globe, 70 whereby when said globe is removed, said cooperating stop portion will prevent the forcing of said section entirely out of said guard by said spring, the remaining section of said element being adjustable endwise of the globe engaging section to vary the effective length of the flue of said element, and means for interlocking the sections of said element mechanically and releasably together in different telescopic, relatively adjustable positions, whereby said element may be shifted as a unit from said remaining section against the action of said spring while the sections are in different adjusted positions to release or grip said globe, and be independently adjusted to vary the effective length of its flue.

3. A lantern comprising a globe seat, a globe on said seat, a chimney guard having a cylindrical passage, a flue element passing through said passage and formed of two telescopic sections, the outer telescopic section having an outwardly projecting peripheral bead engaging and sliding along the walls of said passage, said guard at the lower end 95 of said passage having an inturned flange engaging with the outer section of said element to slidably guide the same and to prevent passage of said bead thereby, the upper end of said outer section having a reduced 100 terminal slidably engaging the inner telescopic section, with a shoulder at the reduced terminal, and a spring acting between said guard and said shoulder to yieldingly urge said outer section downwardly into engagement with said globe, the inner section of said element projecting from said guard and having a portion by which it may be engaged and manipulated endwise to vary the effective length of the flue of said element. 105

4. A lantern comprising a globe seat, a globe on said seat, a chimney guard having a cylindrical passage, a flue element passing through said passage and formed of two telescopic sections, the outer telescopic section having an outwardly projecting peripheral bead engaging and sliding along the walls of said passage, said guard at the lower end of said passage having an inturned flange engaging with the outer section of said element to slidably guide the same and to prevent passage of said bead thereby, the upper end of said outer section having a reduced 115 terminal slidably engaging the inner telescopic section, with a shoulder at the reduced terminal, a spring acting between said guard and said shoulder to yieldingly urge said outer section downwardly into engagement with said globe, the inner section of said element projecting from said guard and having 120

- a portion by which it may be engaged and manipulated endwise to vary the effective length of the flue of said element, and means for interlocking said sections of said element releasably together in different adjusted positions, whereby said sections may be released from one another to permit relative adjustment of the same into different telescopic positions, and selectively locked together to permit manipulation of said sections together as a unit by force applied to said inner section against or by the action of said spring for releasing or engaging a globe.
5. A lantern comprising a globe seat, a globe on said seat, a chimney guard, a flue element engaging the upper end of said globe to confine it to its seat and formed of two telescopic sections, one of said sections having a slot extending endwise thereof with lateral branches therefrom, a pin carried by the other of said sections and engaging in said slot, whereby when one of said sections is rotated relatively to the other section to place said pin in the endwise extending section of the slot, the sections may be adjusted endwise to vary the effective length of the flue of said element, and when rotated to carry said pin into a lateral branch, relative endwise movement of said sections will be prevented, thus permitting operation of said sections together as a unit to release or engage said globe, and independent adjustment of the sections to vary the effective length of the flue thereof, and a spring acting between said guard and one of said sections for urging said element yieldingly into engagement with said globe.
6. A lantern comprising a frame, a globe mounted on said frame, said frame having above said globe a tubular chimney guard with an inturned annular flange at its upper end, a cylindrical collar secured within said guard and having an inner cylindrical wall extending in a direction axially of the guard, a flue element having two telescopic sections passing through said guard with its inner section slidably mounted by the upper inturned flange of said guard and with its outer action 45 supported by said cylindrical collar, means for interlocking said sections releasably to one another to permit their relative adjustment endwise in varying the effective length of the flue of the element, and permitting their movement together as a unit in a direction endwise of said guard, and a spring acting between said guard and one of said sections for urging said element yieldingly into engagement with said globe to confine it in said frame, said outer section having at its upper end an outward projection, and said collar having an inturned projection at its lower end engaging with the outward projection on said lower section, whereby said projections by engagement with

one another will prevent movement of said outer section out of sliding engagement with said collar under the action of said spring.

7. A lantern comprising a frame having a chimney guard, a flue element movable endwise through said guard and formed of two telescopic sections, one of said sections having a slot extending in a direction endwise of the section, with lateral branches, the other of the sections having a pin engaging in said slot, whereby when said sections are given relative rotation to dispose said pin in said endwise slot, the sections may be adjusted endwise to vary the effective length of the flue of said element, and when given relative rotation to dispose said pin in a lateral branch, said sections will be locked together for endwise movement as a unit.

8. A lantern having a globe, a chimney guard, a flue element supported by said guard and releasably engaging with said globe, said element being formed of telescopic sections, said sections having a pin and slot connection to one another by which the sections may be selectively adjusted telescopically to vary the effective length of the flue of said element and be locked together in different positions as a rigid unit when movement to release said globe is desired.

9. A lantern having a globe, a chimney guard, a flue element supported by said guard and engaging with said globe, said element being formed of telescopic sections, said sections having means releasably interlocking them together as a rigid unit and operable to release them for telescopic adjustment in varying the effective length of the flue of said element.

10. A lantern having a globe, a chimney guard above said globe and having a passage vertically from end to end, said guard having separate guiding seats in said passage at different levels spaced materially apart vertically, a flue element passage through said guard passage and formed of telescopic sections, one of said sections being slidably guided solely by one of said guides, and the other section being guided solely by the other of said guides, said sections having sliding engagement with one another, a spring in said guard passage urging the lower of said sections downwardly into engagement with the globe, the other section extending above the guard and being open to discharge flue gases, and means to lock said sections releasably together to hold them in different telescopic operative relations, whereby the effective length of the flue element may be varied during burning of the lantern and the sections manipulated as a unit to release the globe.

11. A lantern having a globe, a chimney guard above said globe and having a passage vertically from end to end, said guard having separate guiding seats in said passage at different levels spaced materially apart ver-

- tically, a flue element passing through said guard passage and formed of telescopic sections one of said sections being slidingly guided solely by one of said guides, and the other section being guided solely by the other of said guides, said sections having sliding engagement with one another, a spring in said guard passage urging the lower of said sections downwardly into engagement with
- 5 the globe, the other section extending above the guard and being open to discharge flue gases and means to lock said sections releasably together to hold them in different telescopic operative relations, whereby the effective length of the flue element may be varied during burning of the lantern and the sections manipulated as a unit to release the globe, each section having portions cooperating with its guide to limit downward movement of that section through the guide.
- 10 12. A lantern having a globe, a chimney guard above said globe and having a passage vertically from end to end, said guard having separate guiding seats in said passage at different levels spaced materially apart vertically, a flue element passing through said guard passage and formed of telescopic sections, one of said sections being slidingly guided solely by one of said guides, and the other section being guided solely by the other of said guides, said sections having sliding engagement with one another, a spring in said guard passage urging the lower of said sections downwardly into engagement with
- 15 the globe, the other section extending above the guard and being open to discharge flue gases, and means to lock said sections releasably together to hold them in different telescopic operative relations, whereby the effective length of the flue element may be varied during burning of the lantern and the sections manipulated as a unit to release the globe, said sections having sliding engagement with one another at a plurality of points
- 20 spaced materially apart along the path of telescopic movement, whereby said sections will be maintained in alignment in all their different telescopic positions.
